UNITED STATES PATENT OFFICE.

GEORGE L. THOMPSON, OF CHICAGO, ILLINOIS.

DESIGN FOR A FRONT FORK FOR VELOCIPEDES.

SPECIFICATION forming part of Design No. 29,245, dated August 16, 1898.

Application filed July 5, 1898. Serial No. 685,178. Term of patent 7 years.

To all whom it may concern:

Be it known that I, GEORGE L. THOMPSON, of Chicago, in the county of Cook and State of Illinois, have invented and produced a new and original Design for a Velocipede-Fork, of which the following is a specification.

My novel design consists in a front fork for a velocipede, and embraces as its distinctive features an oval or U-shaped crown *b*, made smooth and substantially oval in cross-section and having united therewith the pair of fork members *a*, each having the tip portion *a²* and the upper end portion *a³*, adjacent to the crown *b*, made smooth and of generally oval form in cross-section and each made of uniformly angular contour in cross-section, so as to present to view a plurality of flat faces *a'* throughout its portion extending between the said tip and upper end portions, substantially as shown in the accompanying drawings, in which—

Figure 1 is a side elevation. Fig. 2 is a

front elevation, and Fig. 3 a transverse sectional view, taken on line 3 3 of Fig. 1.

The flat faces *a'* are symmetrically arranged 25 and substantially coextensive with each other and merge into the smooth or oval parts in the form of gracefully-tapered points or end portions *a⁴*, thereby contrasting the angular portions of the fork members with the smooth 30 portions thereof and accentuating the characteristic appearance of the design.

I claim as my invention—

The design for a front fork of a velocipede, substantially as herein shown and described. 35

In testimony that I claim the foregoing as my invention I affix my signature hereto, in the presence of two subscribing witnesses, this 30th day of June, A. D. 1898.

GEORGE L. THOMPSON.
